UNITED STATES PATENT OFFICE.

WILLIAM WRIGHT VINCENT, OF KENOSHA, WISCONSIN, ASSIGNOR TO THE SIMMONS MANUFACTURING COMPANY, OF KENOSHA, WISCONSIN, A CORPORATION OF WISCONSIN.

HEATING DEVICE FOR BEDSTEAD-TRIMMINGS.

1,012,035.

Specification of Letters Patent. Patented Dec. 19, 1911.

Application filed March 8, 1909. Serial No. 482,051.

To all whom it may concern:

Be it known that I, WILLIAM WRIGHT VINCENT, a citizen of the United States, residing at Kenosha, in the county of Kenosha and State of Wisconsin, have invented certain new and useful Improvements in Heating Devices for Bedstead-Trimmings, of which the following is a specification.

This invention concerns simple, inexpensive, and conveniently-actuated devices for heating and manipulating small parts to be lacquered or otherwise coated while in a heated condition, such, for example, as the various trimmings, mounts, knobs, and the like used on brass bedsteads. Inasmuch as the heating period is longer than the time consumed in lacquering a single part, I have found it convenient and desirable to arrange such devices in banks or series whereby the knobs or the like can be coated in succession, the others being heated while the particular one being coated is temporarily projected out of the oven or other heating compartment in position for the ready application of the lacquer. After being coated each knob or trimming is removed from its support and replaced by another which will be subjected to the heat during the coating of the remaining knobs of the series.

30 A preferred and desirable embodiment of this invention is set forth in the drawings accompanying this specification and forming a part thereof, like reference characters referring to the same parts throughout the views.

In these drawings—Figure 1 is an end elevation of the appliance, certain parts being broken away to more clearly illustrate the details of construction; Fig. 2 is a vertical section on line 2—2 of Fig. 1, the springs and treadles being illustrated unsectioned; and Fig. 3 is a face view of the heating appliance and the pipes leading thereto, showing one of the sliding shafts bearing a bedstead trimming, another of the shafts with the holder in place, and the remaining shafts with the holders removed.

On a suitably-supported table-top or bench 10 and at the front portion thereof and 50 overhanging the table or bench, as indicated in Fig. 1, I mount a heating oven or hollow casting 11 having a flat base portion 12 secured in any suitable manner to the table-top. This casting is equipped with a plurality of thin inner horizontal tubes 13 each

having a front open mouth, the rear portion of each tube being closed by a centrally-perforated closure or metallic block 14.

From a suitable gas supply pipe 15 a plurality of branches 16, equal in number to 60 the compartments or tubes 13 and each supplied with a controlling valve 17, conduct the gas from such main pipe 15 to the burners 18, the top ends of which project through suitable apertures in the bottom of the casting 11 into the interior thereof. In order to permit access of the external air to the interior of such oven or heating appliance to carry on the gas combustion, the base thereof is equipped with a number of holes 65 19, the products of combustion escaping at the top through the apertures or holes 20. It will, therefore, be apparent that the gas burning within the oven 11 heats the tubes or compartments 13 substantially uniformly 70 75 the fumes or products of combustion not entering such compartments, which are adapted to accommodate the knobs or trimmings during the heating operation.

In alignment with each tube or compartment 13 I provide a pair of bearings 21 in which a shaft 22 is adapted to slide and rotate, the front portion of such shaft projecting through the hole of the plug or closure 14, as is clearly indicated in Fig. 1. 80 85 In the front end of each of these shafts is fitted a conical mount or trimming holder 23 adapted to extend partially within such hollow mount or trimming 24 and hold the same thereon by frictional contact. Each 90 sliding shaft 22 has keyed thereto a grooved pulley 25 rotated by a belt 26, the key-way 27 of the shaft being of considerable length and permitting the shaft to slide in such pulley, the latter being maintained against 95 longitudinal movement with the shaft by a sleeve 28 interposed between the same and one of the bearings 21. It should, therefore, be apparent to those skilled in this art that the belts and pulleys rotate the shafts and 100 that the latter may be slid lengthwise at the same time.

Beneath each oven and shaft I mount a right-angle braced treadle or foot-operated bell-crank 29 fulcrumed on the floor at 30 and pivotally connected at its upper end at 31 to the shaft, a coil contractile spring 32 being connected to the brace of the treadle at 33 and to a depending iron bracket 34 at 35, tending to rock the treadle rearwardly 105 110

on its fulcrum and slide the shaft in a corresponding direction to normally maintain the trimming 24 within the oven or compartment 13. As is clearly indicated in Fig. 1, 5 the upper portions of these bell-crank treadles extend through an aperture in the table-top.

It being assumed that each of the supports or holders 23 has been supplied with 10 a knob or mount 24, the operator, by pressure of his foot upon the first treadle 29, rocks the latter forwardly on its fulcrum in opposition to the action of spring 32 and slides the first shaft 22 forwardly, bringing 15 the knob or trimming carried thereby out of the compartment or oven into a convenient position for the application of the lacquer, which is brushed on during such heated condition of the trimming or mount and during 20 its rotation, it being understood that such knob or trimming is constantly rotated. Such rotation when the knob is in the oven assists in the uniform heating of the same, and when the knob or trimming is projected 25 from the oven permits the operator to readily coat the same. The first trimming or knob having been properly lacquered, it is removed and replaced by another, the workman then lifting his foot from the treadle 30 so that the spring 32 by its contraction shifts the shaft rearwardly, bringing the trimming or mount into the oven for the application 35 of the heat. The workman then projects the second knob or mount in like manner, coats the same, and replaces it with another. The 40 number of compartments and pieces to be lacquered and the heat applied thereto are chosen so that when the last trimming has been coated the mount or knob in the first 45 compartment will have been heated sufficiently to be ready for the application of its protective coating.

Inasmuch as a contrivance of this character is susceptible of considerable modification with respect to its structural features without departure from the heart of this invention, it is to be understood that such invention is not limited and restricted to the exact device shown and described.

60 I claim:

1. In a machine for heating bedstead trimmings, the combination with a heating oven, of a plurality of heating tubes substantially closed at one end extending through said oven, a slidably mounted rotating shaft extending through the closed end of each tube and carrying a holder, means for continu-

ously rotating said shafts, and means for independently sliding said shafts to move the corresponding holders into and out of the open ends of the tubes.

2. In a machine for heating bedstead trimmings, the combination with a heating oven, of a plurality of heating devices in said oven arranged side by side and substantially closed at one end, a longitudinally slideable rotary shaft extending through the closed end of each tube, a holder on the inner end of each shaft, means for rotating said shafts, and means for independently shifting the shafts to carry the holders into or out of the open end of the tubes.

3. In a device of the character described, the combination with a heating oven, of a plurality of heating tubes extending therethrough and spaced away from the side walls of said oven, means for supplying heat to said oven, a plurality of slidably mounted rotary shafts extending into one end of the tubes, a holder for that end of each shaft within the tube, means for rotating said shafts and means for shifting said shafts to carry the holders out of the opposite ends of the tubes.

4. In a device of the character described, the combination with a gas oven, of a heating tube extending therethrough open at one end but sealed against communication with the interior of the oven, a slideable shaft extending through a suitable aperture in the closed end of the tube adapted to carry a piece to be heated and coated, and means for sliding said shaft to carry said piece into said heating tube and out through the open end of the tube.

5. In a device of the character described, the combination with a heating oven, of a plurality of heating devices in said oven open at one end but sealed against communication with said oven, a slidably mounted rotary shaft extending through an aperture in the closed end of each tube and adapted to hold the piece to be heated, means for rotating said shafts, and a plurality of independently movable treadle mechanism for longitudinally shifting said shafts separately to carry the pieces to be heated into the tubes and to shift them out of the open ends of the tubes when heated to be coated.

WILLIAM WRIGHT VINCENT.
